(57) **CLAIM**

I claim the ornamental design for a pressure release lever, as shown.

DESCRIPTION

FIG. 1 is an isometric view showing the top, left side, and front of the pressure release lever of the invention.

FIG. 2 is an isometric view showing the bottom, right side, and front of the pressure release lever of the invention.

FIG. 3 is a top plan view of the pressure release lever of the invention.

FIG. 4 is a bottom view of the pressure release lever of the invention.

FIG. 5 is a rear elevation of the pressure release lever of the invention.

FIG. 6 is a front elevation of the pressure release lever of the invention; and,

FIG. 7 is a left side elevation of the pressure release lever of the invention.

The right side of the pressure release lever of the invention is identical to the left side as illustrated in FIG. 7.
